UNITED STATES PATENT OFFICE.

JOHN TYLER, OF BOSTON, MASSACHUSETTS.

MACHINE FOR INDICATING THE FORCE OF BLOWS.

SPECIFICATION forming part of Letters Patent No. 358,706, dated March 1, 1887.

Application filed June 16, 1886. Serial No. 205,331. (No model.)

To all whom it may concern:

Be it known that I, JOHN TYLER, of Boston, in the county of Suffolk and State of Massachusetts, a citizen of the United States, have 5 invented a new and useful Improvement in Machines for Indicating the Force of Blows, of which the following is a full, clear, and exact description, reference being had to the accompanying drawings, forming a part of this specification, in describing its nature.

The object of the invention is to provide a simple and inexpensive instrument for indicating the force of blows; and it comprises various details of construction and organization, all of 15 which will hereinafter be described.

Referring to the drawings, Figure 1 is a view in plan of my improved apparatus. Fig. 2 is a vertical central section thereof. Fig. 3 is a front elevation. Fig. 4 is a rear elevation, and 20 Fig. 5 a vertical section illustrating a modified form of holding device.

A represents a cast-iron frame, having a tubular section, a , adapted to receive and hold the resistant spring A' and the bracket or arm 25 A^2 , which is cast therewith. The resistant spring is held within the tube or hole a' of the frame, so as to bear against the shoulder a^2 and against the pin a^3 , which is fastened to the spindle, rod, or bar B, which carries the pad 30 or device C, against which the blow is struck or delivered, and both the spring and the bar, spindle, or rod are held in place by the cap D, which has a hole, d , through which the bar, spindle, or rod passes, and a lug, d' , which 35 hooks onto the lug d^2 on the casing a , and which projects upon the arm A, and is held in place thereto by the screw d^3 and nut d^4 . The cross-pin a^3 , extending across the bar or rod, serves, in connection with the cap, as a 40 stop in limiting the outward movement of the bar, and the resistant spring is arranged to bear against this pin.

The bar B supports at its outer end a bell or support, c , and this bell or support is 45 secured to the end of the bar, rod, or tube by means of the lugs c' , which overlap the head c^2 of the bar, rod, or tube, and the screws c^3 , which pass through the lugs and head c^2 . The bell is filled with hair or other elastic or yielding 50 material and supports a leather cover, c^4 , which is fastened thereto by a clamping-band, c^5 . The bar, rod, or spindle also has a scale,

E, upon one side, which preferably is made of brass or other similar material, and fastened thereto by screws, and there is arranged to 55 slide upon the bar, rod, or tube a pointer or indicator, e , which comprises a band which surrounds the bar, rod, or tube on three sides, and is held together on the fourth side by a spring, e' , so as to cause the band to bear with 60 sufficient friction to hold the indicator in its place.

In use the indicator is moved inward to bring it to zero, and upon striking or punching the pad the rod, tube, or bar is moved inward, the 65 indicator remaining stationary during such inward movement, and at the end thereof moving outward with the bar, rod, or tube, and thereby indicating the extent of the inward movement thereof, so that the extent of the 70 compression of the spring is shown.

The arm or bracket A^2 carries a clamp-plate, F, which is pivoted to the end thereof. There is also secured to the frame an independent arm, A^3 , which carries another clamping-plate, 75 F', which is also pivoted to the end thereof, and which is adapted to be locked in place by a set-screw, f .

The independent arm A^3 is made movable upon the tubular part of the frame, and is provided with a clamp, f' , by which it is locked thereto. These two clamping-plates F F' serve to lock the device to a door-frame, window-casing, pillar, or any other convenient place. 85

For the purpose of suspending the device or implement from a bracket or other support, I employ an arm, G, which is in some respects similar to the arm A^3 . It is movable upon the tubular part of the casing or frame A, has a clamp, g , by which it is fastened rigidly thereto, and carries at its end a plate, g' , which is pivoted to the end of the arm, and has holes g^2 , for the reception of bolts or screws for securing it to a bracket or arm, and also the holes 90 g^3 , for receiving a bolt or pin for locking the arm G rigidly thereto, the arm G having one hole, g^4 , which receives such locking pin or nut.

I have represented the plate g' as having three holes, g^3 , which of course will provide 100 for three different adjustments of the device; but as many holes for this purpose may be used as may be necessary.

This construction and organization of in-

strument for indicating the force of blows is cheap and simple, and it provides means whereby it can be easily placed in position and moved from one point to another.

5 The faces of the clamping-plates F F' may be lined or covered with felt to protect the support to which the device is attached.

Having thus fully described my invention, I claim and desire to secure by Letters Patent 10 of the United States—

1. In a device for indicating the force or strength of a blow, for gymnasiums and other purposes, the combination of a casing or frame comprising a casting having a hole for the reception of the resistant spring, the bracket or arm A², carrying the clamp-plate F, and the independent arm A³, carrying a clamp-plate, F', with said resistant spring confined in said hole, the bar, rod, or tube B, supporting the 15 pad or other similar device, the cap D, secured in place as indicated, and the pin a³, substantially as described.

2. In a device for indicating the force or strength of a blow, for gymnasiums and other purposes, the combination of a frame comprising a casting having the tubular section a, the arm A², holding a pivoted clamping-plate, F, the movable arm A³, a clamp for fastening it to the tube, its clamping-plate F', and locking-screw f, the resistant spring A', rod, bar, or tube B, and the pad C, substantially as described. 25

3. The combination of a support for a resistant spring, having means for fastening it to a door-frame, post, or other device, or for suspending it, the said resistant spring, a bar, 30 rod, or tube carrying at its end a striking-pad, a scale carried by said rod, bar, or tube, and an indicator held thereon by friction, all substantially as described.

JOHN TYLER.
